BY

Frank J. Baldwin
ATTORNEY

UNITED STATES PATENT OFFICE

ROBERT JAMES GORDON CHURCH, OF DETROIT, MICHIGAN

TOOTHERBRUSH

Application filed November 21, 1929. Serial No. 408,832.

This invention relates to improvements in toothbrushes, and aims, among other things, to provide a toothbrush having a dental floss container thereon towards the extremity of the handle remote from the bristles, and with the container projecting at an angle to the direction of the intermediate portion of the handle so that the latter may be employed as a bow from which a portion of the floss is spaced when held taut between one holding means on the handle adjacent the bristles and a second holding means on the container.

I am aware that it has been customary to provide a dental floss container at the outer end of a toothbrush handle on which rearward projections are arranged so that a portion of the floss may be stretched between the projections. In the present invention the brush is compact, and no rearward extensions are required as the intermediate portion of the handle is utilized as a bow away from which the floss is spaced; moreover the distance between the holding means for the extremities of the outstretched floss is such that an ample length of the latter is provided for teeth cleaning purposes.

With these and other objects and advantages in view which will become apparent as the specification proceeds, the invention is hereinafter more fully described with the aid of the accompanying drawings, in which:

Figure 1 illustrates a side elevation of a straight handled toothbrush having a container mounted on the handle adjacent its end remote from the bristles, and

Figure 2 is a front view thereof.

Figures 3 and 4 show side views of the invention wherein the container and the brush handle are integral, and

Figure 5 is an enlarged view of the container cap.

Referring to the drawings, 1 designates a toothbrush handle provided at one end with ordinary bristles 2. 3 denotes a container at the opposite end of the handle which projects at an angle to the intermediate portion of the latter. In Figures 1 and 2 the container is separate from the handle and is secured thereto by fastening means 3a which pass through the container flanges 3b and take

into the handle; and in Figures 3 and 4 the container is integral with and formed in the handle 1. 4 indicates a suitable binding post or projection on the handle adjacent the bristles 2 around which a portion of a thread may be wound to hold it against movement. A cap 5 is removably mounted on the outer end of the container 3 and has an aperture 6 therethrough and outward projections 7 and 7a formed thereon.

A spool of dental floss 8 is arranged in the container 3 and a thread 8a of the floss extends through the aperture 6, is coiled around the projections 7 and 7a to hold that portion against movement, and the extremity of the thread is secured around the binding post 4.

Due to the fact that the container is arranged at an angle to the direction of the intermediate portion 1a of the handle and also to the fact that the binding post 4 projects from the same side of the handle as the container 3 the said intermediate handle portion may in any case be utilized as a bow from which the thread portion 8a between the projections 7 and 7a and the binding post 4 is, when held taut by the fastening means, sufficiently spaced to permit its being employed for cleaning around and between the teeth.

In the construction shown the projections 7 and 7a are formed integral with the cap 5 which is made in the form of a stamping, in which case the threaded flange 5a of the cap is also formed in the dies without the aid of machining but obviously caps made otherwise may also be utilized if desired.

While in the foregoing the preferred embodiments of the invention have been described and shown, it is understood that the construction is susceptible to such further alterations and modifications as fall within the scope of the appended claims.

What I claim as my invention and desire to secure by Letters Patent is:

1. In a toothbrush, the combination of a handle having bristles mounted thereon towards one extremity, a container towards the opposite extremity of the handle inclined at an angle to the intermediate portion of the latter, said container being adapted to

hold dental floss, and two fastening means, one on the container and the other on the handle adjacent the bristles each adapted to have a portion of a thread of dental floss secured to them so that that portion of the thread which lies between them is held taut and is spaced from the intermediate portion of the handle.

2. A toothbrush consisting of a handle having bristles mounted thereon towards one extremity, a container towards the opposite extremity of the handle inclined at an angle to the intermediate portion of the latter, a cap on said container having an aperture therethrough through which a thread of dental floss contained in the container extends, means on the cap for holding one portion of the thread, and means on the handle adjacent the bristles for holding another portion of the thread so that that portion of the thread which lies between the two holding means is held taut and spaced from the intermediate portion of the handle.

3. A toothbrush consisting of a handle having bristles mounted thereon towards one extremity, a container formed in the handle adjacent its other extremity, the container lying obliquely relative to the extremity of the handle on which the bristles are mounted, a removable cap on said container having an aperture therethrough through which a thread of dental floss contained in the container extends, means on the cap for holding a portion of the thread, and means on the handle adjacent the bristles for holding another portion of the thread so that that portion of the thread which lies between the two holding means may be held taut and spaced from the intermediate portion of the handle.

ROBERT JAMES GORDON CHURCH.
